[57] CLAIM

The ornamental design for a brassiere, as shown and described.

DESCRIPTION

FIG. 1 is a front elevational view of a brassiere showing my new design;

FIG. 2 is a top plan view thereof;

FIG. 3 is a rear elevational view thereof;

FIG. 4 is a bottom plan view thereof; and

FIG. 5 is a left side elevational view thereof, the right side being a mirror image;

The broken lines shown throughout the views represent conventional stitching.

FIG. 1

FIG. 2

FIG. 3

FIG. 5

FIG. 4
